UNITED STATES PATENT OFFICE.

CHARLES H. REEDER, OF ST. LOUIS, MISSOURI.

UNLOADING DEVICE FOR AIR-COMPRESSORS.

1,365,272.

Specification of Letters Patent. Patented Jan. 11, 1921.

Application filed February 13, 1920. Serial No. 358,359.

To all whom it may concern:

Be it known that I, CHARLES H. REEDER, a citizen of the United States of America, and a resident of the city of St. Louis and

5 State of Missouri, have invented certain new and useful Improvements in Unloading Devices for Air-Compressors, of which the following is a full, clear, and exact description, reference being had to the accompanying drawings, forming a part of this specification.

10 This invention relates to improvements in unloading devices for air compressors and the like. An object of the invention is to produce a simple and inexpensive automatic means whereby a motor driven compressor is permitted to run idly when the motor is started, and thereafter permitted to begin its effective operation when the motor is running at a comparatively high speed. 15 This enables the motor to run freely during the starting period, and to pick up the load while it is running at a predetermined operating speed.

20 Briefly stated, the device I have shown to illustrate one form of the invention, comprises a relief valve, or unloading valve, adapted to open and close the compression chamber of the compressor, electrically actuated means controlling said relief valve to retain the latter in its open position during the starting period, and a speed responsive switch controlling the electrical means, to permit closing of the relief valve when the 25 compressor is driven at a predetermined operating speed.

25 The drawing is a diagrammatical view illustrating a motor driven compressor provided with an unloading device embodying the features of this invention.

30 An electric motor 1 is provided with an armature shaft 2 whereby a crank 3 is driven. The crank may be directly connected to the motor, as shown in the drawing, or any 35 other suitable means may be employed to transmit motion to the crank. The compressor may include a cylinder 4 containing a piston 5, and a connecting rod 6 whereby the piston is connected to the crank 3.

40 7 designates a relief valve, or unloading valve, which may be considered as the inlet valve of the compressor. This valve is adapted to open and close a port 8 so as to control communication between the compression chamber and the atmosphere. I do not

deem it necessary to show the discharge valve nor the operating means therefor, these elements being old and well understood in the art to which my invention relates.

45 When the motor is idle, and also during the starting period, the valve 7 is held in the open position shown in the drawing, and the piston 5 can then move freely without compressing air in the cylinder. When the motor operates at a predetermined speed, the valve 7 is automatically released, as hereafter pointed out, and permitted to close the port 8, so as to provide for compression of air in cylinder 4.

50 9 designates a spring surrounding the stem 70 of valve 7 and interposed between a valve-guide 10 and a head 7' at the upper end of the valve stem. This spring 9 tends to close the relief valve 7.

55 The means for controlling the relief valve 75 7 preferably comprises an electro-magnet 12, which may be in the form of a solenoid having core 13 adapted to engage the head 7' at the upper end of the valve stem. When the solenoid is energized, its magnetic force 80 will lift the core 13, thereby releasing the valve 7 and permitting the spring 9 to close said valve. When the solenoid is deenergized, the core 13 will drop by gravity to open the valve 7, as shown in the drawing. 85 If desired, the core 13 may be enlarged at its lower end to provide additional weight.

60 The means for energizing the solenoid includes a conductor 14 leading directly to the solenoid, and a conductor 15 provided with a switch, consisting of a movable spring contact member 16 and a fixed contact 17. When the apparatus is idle, the switch occupies the open position shown in the sketch, and the solenoid core 13 then holds the 95 valve 7 in its open position. When the apparatus is in operation, a speed responsive device acts upon movable contact 16 to retain it in engagement with contact 17, thereby closing the switch through which current 100 flows to the solenoid.

65 The speed responsive elements may be constructed in any suitable manner. To illustrate this feature I have shown a shaft section 18 extending from the crank 3 and provided with a wheel or housing 19 containing a speed responsive device consisting of weighted arms 20 pivoted at 21 to the housing and extending into an annular groove formed in a sleeve 22, the latter being slid- 110

able on shaft 18. A spring 23 tends to retain sleeve 22 in the position shown in the sketch. This sleeve 22 has an annular flange 24 adapted to engage the movable switch member 16. As the speed increases, the weighted arms 20 will swing in response to centrifugal force, so as to move the sleeve 22, thereby closing the switch 16-17.

It will now be understood that the relief valve 7 is held in its open position until the electric motor is operating at a predetermined speed, whereupon the switch 16-17 will be automatically closed, to complete the electric circuit whereby the solenoid is energized to release the valve 7, so there will be no substantial load on the motor until it is running at a predetermined operating speed. The device herein disclosed will respond automatically to the operations of starting and stopping the motor. When the motor is idle, and when it is operating at low speeds, the automatic switch 16-17 will be open and the solenoid core 13 will then retain the relief valve 7 in its open position, but when the motor is running at a speed high enough to effectively drive the compressor, the speed responsive switch will be closed, so as to permit the transmission of electric current to the solenoid, whereby the core 13 is held in an inoperative position beyond the path of the head 7' at the upper end of the valve stem.

I claim:

1. A motor driven compressor provided with a relief valve arranged to open and close the compression chamber of the compressor, a valve opening device adapted to retain said relief valve in its open position, an electro-magnet whereby said valve opening device is actuated to permit closing of said relief valve, a spring tending to close said relief valve, a switch controlling the transmission of current to said electro-magnet, and a speed responsive device whereby said switch is actuated, said speed responsive device being driven by the motor so as to retain the switch in its closed position during normal operating speeds.

2. A motor driven compressor provided with a compression chamber having an opening through which fluid may be drawn into and discharged from the compressor, a pressure-relieving valve arranged to open and

close said opening, a valve opening device adapted to retain said pressure-relieving valve in its open position, an electro-magnet whereby said valve opening device is actuated, a switch controlling the transmission of current to said electro-magnet, and a speed responsive device whereby said switch is actuated, said speed responsive device being driven by the motor so as to provide for operation of said switch and pressure-relieving valve when the motor and compressor are operated at a predetermined speed.

3. A motor driven compressor provided with a relief valve adapted to open and close the compression chamber of the compressor, a valve opening device adapted to contact with said relief valve to retain it in its open position, a spring tending to close said valve, a magnet controlling said valve opening device whereby it is actuated to permit said spring to close the relief valve, a switch controlling transmission of current to said magnet, and a speed controlled device driven by the motor and operatively connected to said switch whereby said switch is retained in its closed position during normal operative speeds of the motor but is permitted to open when the motor speed is below normal.

4. A motor driven compressor provided with a relief valve adapted to open and close the compression chamber of the compressor, a spring means tending to close said relief valve, a weight tending to hold said relief valve in a normally open and inoperative position and adapted to overcome the closing tendency of said spring means, an electro-magnet controlling said weight and adapted to lift it to permit the spring means to close said relief valve, a switch controlling said electromagnet, and a speed controlled device driven by the motor whereby said switch is actuated, said speed controlled device maintaining said switch closed at all speeds above normal speeds of the motor and permitting said switch to open below normal speed of the motor whereby the electro-magnet is energized during the normal operative speed of the motor and deenergized during lesser speeds.

In testimony that I claim the foregoing I hereunto affix my signature.

CHARLES H. REEDER.
